Patented Dec. 24, 1918.

UNITED STATES PATENT OFFICE.

ANGER C. CARLSON, OF BUTLER, PENNSYLVANIA.

WASHING-MACHINE.

1,288,831.

Specification of Letters Patent. Patented Dec. 24, 1918.

Application filed December 6, 1915. Serial No. 65,291.

To all whom it may concern:

Be it known that I, ANGER C. CARLSON, a citizen of the United States of America, residing at Butler, in the county of Butler 5 and State of Pennsylvania, have invented new and useful Improvements in Washing-Machines, of which the following is a full, clear, and exact description, reference being had to the accompanying drawings, which 10 form part of this specification.

The primary object of my invention is to provide means whereby the water used in a washing machine may be conveniently kept at a temperature which shall facilitate 15 and improve the work usually done by such machines. As such a device I provide water heating means that is simple in construction, may be easily attached to the machine and may be kept in operation without continued 20 attention on the part of the operator.

I will now describe my invention so that others skilled in the art to which it appertains may understand and construct the same, it being premised however that changes 25 may be made in the structures shown and described without departing from the invention claimed.

Figure 1 is a fragmentary view of a rotatable wash tub and its support, showing my 30 invention applied thereto:

Fig. 2 is a fragmentary view showing a modified form of heating means, and

Fig. 3 is a fragmentary view of the inside of the tub bottom showing the tank connection with the tub bottom.

Referring to the drawing, the reference numeral 2 indicates the tub portion of an ordinary washing machine of the type in which the tub itself is rotatable, as for instance, for coöperation with a stationary dasher. Communicating with the tub through the bottom wall 3, is a water tank 4. This tank, which is preferably constructed of thin sheet metal to obtain the 45 maximum conductivity of heat, and is relatively small and drum-like in appearance, has its connection with the bottom of the tub by means of a pipe 5 carrying a flange or head 6 which abuts against the under 50 face of the tub body and coöperates with a top plate 7 through connecting bolts or fastening means 8 to effect a proper seal. The plate member 7 is preferably provided with a plurality of perforations 7^a, which, while 55 allowing for communication between the tub

chamber and tank, are of such size as to prevent small articles in the tub, from working down into the mouth of the pipe 5. The tank is also provided with a capped drain outlet 9.

In order not to interfere with the action of the rotating tub, the pipe 5 passes through an opening 14 in the stationary support or housing 15 of the washing machine; the opening 14 being of ample size to allow the 60 pipe 5 to rotate freely with movement of the tub 2 upon the ball-bearing 16.

Disposed beneath the tank 4 is a gas burner 10 supported by a standard or bracket 11 that is carried on a suitable base board 12 mounted across the foot rods or braces 13, as clearly shown.

It will of course be understood that with water in the tub, a portion of it will pass to the tank. Any air that may be imprisoned in the tank, incident to sudden charging of the water in the tank may be freed by opening the drain 9 or it will be released upon agitation of the water set up in the washing of the clothes. When the 70 tank has thus been filled with water, the gas burner 10 or oil burner 17 (Fig. 3) disposed beneath the tank, may be lighted. The heat thus generated quickly penetrates the thin metal of the tank and brings the 75 temperature of the water therein to a high point. This water in turn quickly communicates its heat to the larger body of water in the tub, and the steam thus generated greatly facilitates and improves the 80 work done by the washing machine.

Having thus described my invention, what I claim and desire to secure by Letters Patent is:

In combination with a rotatable wash tub and its support, a heater comprising a tank disposed below the bottom of said tub and below the top of said support, and a vertical pipe connected and communicating with said tank centrally of the top thereof and connected and communicating with said tub centrally of its bottom wall, said support being provided with a hole permitting the passage of said pipe, said tank being rotatable with said tub, and a burner disposed 95 below said tank and stationary in respect to said support.

In testimony whereof I have hereunto set my hand.

ANGER C. CARLSON.
